UNITED STATES PATENT OFFICE.

FRANCIS E. YOUNG, OF BOSTON, MASSACHUSETTS, ASSIGNOR TO SPRAY ENGINEERING COMPANY, OF BOSTON, MASSACHUSETTS, A CORPORATION OF MAINE.

SPRAY-NOZZLE.

1,196,627.

Specification of Letters Patent. Patented Aug. 29, 1916.

Application filed August 19, 1915. Serial No. 46,363.

To all whom it may concern:

Be it known that I, FRANCIS E. YOUNG, a citizen of the United States, and a resident of Boston, in the county of Suffolk and 5 State of Massachusetts, have invented an Improvement in Spray-Nozzles, of which the following description, in connection with the accompanying drawings, is a specification, like characters on the drawings representing like parts.

This invention relates to spray nozzles intended for use in various relations.

In order that the principle of the invention may be readily understood, I have disclosed a single embodiment thereof in the accompanying drawings, wherein—

Figure 1 is a vertical, sectional view of a spray nozzle constructed in accordance with my invention; Fig. 2 is a horizontal section 20 upon the line 2—2 of Fig. 1; and Fig. 3 is a side elevation of one of the liquid distributing elements of the nozzle.

The nozzle herein disclosed is adapted for use in many different relations, but is particularly intended for use as a lawn sprinkler. To that end, it is provided with a heavy, hollow, metallic base 1 having a removable, threaded plug 2 through the bottom, permitting access thereto, and with a 25 threaded opening 3, to which a hose or other supply pipe may be attached. The said base has a flattened bottom 4 of considerable area, so that the structure cannot readily be overturned. The shape of said base may 30 be varied within the scope of my invention. The said base is herein represented as provided with an upright neck portion 5, herein shown as provided with an annular flange 6 and an externally threaded nipple 40 7 adapted to receive thereon a member 8 internally threaded as indicated at 9, said member 8 constituting a portion of the nozzle proper.

The shell or member 8 is provided with a 45 transverse web 10 somewhat widened at its middle portion 11 and there internally threaded, as represented at 12, for the reception of an axial stem or plug 13, herein shown as having a solid, lower end of reduced diameter, and an upper portion 14 of increased diameter providing a shoulder 15 adapted to seat upon said web 10. Preferably from the shoulder 15 to a point near the upper end of said stem or plug, it is pro-

vided with a preferably radial slot 16 in 55 communication at its lower end with the interior of the shell or member 8, and hence with the interior of the base 1. The said slot 16 is herein represented as curved or arcuate in vertical section and as terminating at a point slightly below the extreme upper edge of said stem or plug, and herein at substantially the point 17. The portion 14 of the said stem or plug is externally threaded as indicated at 18 for the reception 60 of a secondary shell 19 and is also provided with external helical grooves 20 for the distribution of the water or other liquid to be discharged from the nozzle. Between the upper end of the threaded portion 18 and 65 the helical grooves 20, the said stem or plug is of reduced diameter, as indicated at 21. The said stem or plug 13 is provided with an axial passage 22, which is in communication with the slot 16.

The secondary shell 19 is internally threaded as represented at 23 and is provided with an annular flange 24, the under face 25 of which is adapted to be brought into contact with or to be spaced from the 80 upper edge 26 of the shell or member 8. Said secondary shell 19 is formed to provide a chamber 27, herein represented as tapered at 28 at its upper end and terminating in a discharge opening 29.

Within the shell or member 8 and preferably above the web 10, I provide an annular series of vanes, shown detached at 30 in Fig. 3. While these vanes may be integral with some other portion of the structure, I 90 preferably form the separate vanes 31 by striking them up from a ring 32. The said vanes and the ring may be formed of some suitable sheet metal, such as brass, the vanes being struck up from the ring which may be 95 circumferential and radially slotted for that purpose. As herein shown, I provide six vanes each extending a corresponding distance circumferentially about the ring. In order to position the said ring with its 100 vanes, I preferably provide it with an inwardly extending lug 33, which is adapted to be received within the slot 16. Said ring is therefore capable of axial movement in the operation of the nozzle and may be 105 readily removed upon removal of the secondary shell 19. It is, however, held from circumferential movement by the said lug.

33. An outwardly flaring conical sheet of fluid is discharged between the shells 8 and 19. The vanes 31 tend to impart to the particles of fluid motion in paths diverging from the longitudinal axis of the nozzle, and oblique to the elements of the cone. The helical grooves may be formed upon the axial stem or plug 13, or if desired they may be formed upon the inner surface of the secondary shell 19.

In operation, a plurality of streams are admitted into the secondary shell 19 and are thoroughly mixed therein prior to their discharge through the axial passage 29, so that in this embodiment of my invention, the spray as discharged is of substantially homogeneous structure throughout. The spray discharged between the two shells 8 and 19 may be varied in amount by adjusting the latter shell.

The base 1, which is relatively large and heavy and is preferably of circular form in cross section, is substantially non-tipping. Because of its flat bottom 4, it may be readily placed at any desired point upon a lawn or elsewhere, and the nozzle may be operated without any danger whatever of upsetting.

Having thus described one illustrative embodiment of my invention, I desire it to be understood that although specific terms are employed, they are used in a generic and descriptive sense and not for purposes of limitation, the scope of the invention being set forth in the following claims.

Claims:

1. A spray nozzle including inner and outer shells defining a chamber having an annular discharge opening, means to supply fluid to said chamber, said inner shell having an axial discharge opening and a slot to place said opening in communication with said chamber, a ring in said chamber having vanes and a lug on said ring entering said slot.

2. A spray nozzle having an annular discharge orifice arranged to pass an outwardly flaring conical sheet of fluid, means to introduce the fluid into the nozzle at a point nearer to the longitudinal axis of said nozzle than is the said annular discharge orifice, and means to impart to the particles of fluid of said sheet motion in paths divergent from the longitudinal axis of the nozzle and oblique to the elements of the cone, said means including a ring 30 structurally distinct from the body of the nozzle and having upwardly extending wings 31.

3. A spray nozzle including an outer, open-ended shell, a central stem therein having an axial opening, a second shell mounted on said stem and co-operating therewith to form rotation-inducing passages about said axial opening, said shell providing a mixing chamber for the discharge from said open-

ing and passages, and co-operating with said first shell to form an annular discharge opening therefor.

4. A spray nozzle including an outer, open-ended shell, a central stem therein having an axial opening, a second shell adjustably mounted on said stem and co-operating therewith to form rotation-inducing passages about said axial opening, said shell providing a mixing chamber for the discharge from said opening and passages and co-operating with said first shell to form an annular discharge opening therefor adjustable in width.

5. A spray nozzle including an outer, open-ended shell, a central stem therein having an axial opening, a second shell mounted on said stem and co-operating therewith to form rotation-inducing passages about said axial opening, said shell providing a mixing chamber for the discharge from said opening and having a conical portion adjustable with respect to said first shell to provide a regulable annular discharge opening.

6. A spray nozzle having a basal shell provided with an axial stem, the latter having a longitudinal passage therethrough, and a helical passage thereabout, and a secondary shell supported upon said stem and having an axial discharge, said shells having adjacent portions providing between them a circumferential discharge leading to the exterior of the nozzle at a point distinct from the point of ultimate discharge of the said longitudinal passage.

7. A spray nozzle having a basal shell provided with an axial stem, a secondary shell supported thereon and having an axial discharge, said shells having portions in close proximity to provide between them a circumferential discharge opening leading to the exterior of the nozzle at a point distinct from the point of ultimate exit of said axial discharge, and means for effecting a mixing of a plurality of streams within said secondary shell.

8. A spray nozzle having a basal shell provided with an axial stem, a secondary shell supported thereon, and means for effecting the mixing of a plurality of streams therein, said shells having their walls in close proximity for effecting the ultimate circumferential discharge of liquid therebetween at a point in the rear of the forward end of said axial stem.

9. A spray nozzle having a basal shell provided with an axial stem having an axial passage, an external thread for the reception of a secondary shell, and a liquid-distributing helix and a secondary shell supported upon said external thread and relatively positioned with respect to the basal shell to permit the ultimate discharge of liquid at a point distinct from the ultimate discharge from said axial passage.

10. A spray nozzle having a basal shell provided with an inner stem, having a slot, and a vane ring within the shell and having a positioning lug extending into said slot, said nozzle having an annular discharge orifice. 5
11. A spray nozzle having a basal shell provided with an inner stem having a slot, a vane ring within the shell and having a 10 positioning lug extending into said slot, and a secondary shell mounted upon said stem and having an axial discharge. 15
12. A spray nozzle including an outer shell, a stem therein having a longitudinal opening, a second shell mounted on said stem and co-operating therewith to form rotation-inducing passages about said opening, said shell providing a mixing chamber for the discharge from said opening and 20 passages, and co-operating with said first shell to form an annular discharge opening therefor. 25
13. A spray nozzle having an annular discharge orifice arranged to pass an outwardly flaring sheet of fluid, means to introduce the fluid into the nozzle at a point nearer the longitudinal axis of said nozzle than is said annular discharge orifice, and means between said introducing means and 30 said annular discharge orifice to impart to the particles of fluid of such sheet motion in paths divergent from the longitudinal axis of the nozzle and oblique to the elements of the cone, said nozzle including a shell 19 at 35 one end of which said annular discharge orifice is provided, said shell having means to discharge a jet at its opposite end. 40
14. A spray nozzle having an annular discharge orifice arranged to pass an outwardly flaring conical sheet of fluid, means to impart to the particles of fluid motion in paths oblique to the elements of the cone, and means to discharge from said nozzle a conical jet composed of inner and outer commingled streams and distinct from that issuing 45 from said annular discharge orifice. 50
15. A spray nozzle having an annular discharge orifice, arranged to pass an outwardly flaring conical sheet of fluid, means to 55 impart to the particles of fluid motion in paths oblique to the elements of the cone, said nozzle having means to discharge in a longitudinal direction therefrom a conical jet composed of inner and outer commingled streams and distinct from that issuing 60 from said annular discharge orifice. 65
16. A spray nozzle having an annular discharge orifice arranged to pass an outwardly flaring conical sheet of fluid, means to 65 impart to the particles of fluid motion in paths oblique to the elements of the cone, said nozzle having a mixing chamber in advance of 70 said annular discharge orifice and a discharge opening in communication with said mixing chamber. 75
17. A spray nozzle having an annular discharge orifice arranged to pass an outwardly flaring conical sheet of fluid, means to impart to the particles of fluid motion in paths oblique to the elements of the cone, said nozzle having a mixing chamber in advance of 70 said annular discharge orifice and a discharge opening in communication with said mixing chamber, and means to impart 75
18. A spray nozzle having an annular discharge orifice arranged to pass an outwardly flaring conical sheet of fluid, means to impart to the particles of fluid motion in paths oblique to the elements of the cone, said nozzle having a mixing chamber in advance of 80 said annular discharge orifice and means to admit an axial and a surrounding jet to the mixing chamber, the latter having a discharge orifice. 85
19. A spray nozzle having a basal shell provided with an axial stem, the latter having a longitudinal passage therethrough, and a helical passage thereabout, and a secondary shell supported upon said stem, and having an axial discharge, the lower portion of 90 the secondary shell coacting with the basal shell, to provide a circumferential discharge. 95
20. A spray nozzle having a basal shell provided with an axial stem, the latter having a longitudinal passage therethrough, and a helical passage thereabout, and a secondary shell supported upon said stem, and having an axial discharge, the lower portion of 100 the secondary shell being adjacent to the upper portion of the basal shell to provide a circumferential discharge. 105
21. A spray nozzle to mix streams of liquid, and having a basal shell provided with an axial stem, the latter having a longitudinal passage therethrough and a helical passage thereabout, and a secondary shell supported upon said stem and having an axial discharge, said shells having provisions 110 for effecting a circumferential ultimate discharge of liquid therebetween at a point distinct from the point of ultimate discharge from said longitudinal passage. 115
22. A spray nozzle having a basal shell provided with an axial stem, a secondary shell supported thereon, and means for effecting the mixing of a plurality of streams 120 therein, said shells having their walls in close proximity for effecting the ultimate circumferential discharge of liquid therebetween at a point in the rear of the means for effecting the mixing of a plurality of streams in said secondary shell. 125
23. A spray nozzle having an annular discharge orifice arranged to pass an outwardly flaring conical sheet of fluid, means to introduce fluid into the nozzle, and means including an annular series of vanes 31 to impart to the parts of fluid of said sheet mo- 130

tion in paths divergent from the longitudinal axis of the nozzle and oblique to the elements of the cone, said nozzle including a shell 19 at one end of which said annular discharge orifice is provided, said shell having means to discharge a jet at its opposite end.

24. A spray nozzle having an annular discharge orifice arranged to pass an outwardly flaring, conical sheet of fluid, means to impart to the particles of fluid motion in paths oblique to the elements of the cone, and

means to discharge from said nozzle a jet of constituent inner and surrounding streams mixed before emission and distinct from that 15 issuing from said annular discharge orifice.

In testimony whereof, I have signed my name to this specification, in the presence of two subscribing witnesses.

FRANCIS E. YOUNG.
